UNITED STATES PATENT OFFICE.

ALEXANDER P. VREELAND, OF LANSING, MICHIGAN, ASSIGNOR, BY MESNE ASSIGNMENTS, TO METAL & THERMIT CORPORATION, OF CARTERET, NEW JERSEY, A CORPORATION OF NEW JERSEY.

METHOD AND APPARATUS FOR CASTING METAL.

Application filed July 3, 1922. Serial No. 572,385.

This invention relates to a method and apparatus for casting metal, and more particularly for casting a metallic part upon a metallic body.

An object of this invention is to provide a method of casting metal around a metallic body clamped between the sections of a mold so that leakage of molten metal between the mold sections is prevented.

Another object of the invention is to provide a mold for carrying out the improved process, the mold being capable of withstanding considerable pressure to tightly clamp a metallic body between the mold sections.

A further object of the invention is to produce a press capable of applying in a uniform manner substantial pressure to the mold to hold the sections tightly together around the periphery to prevent leakage of molten metal. The provision of means to apply the pressure uniformly to the mold sections permits the use of sand molds when desired and it is still possible to apply a relatively high pressure to clamp the mold sections together.

Another object of the invention is to provide a method and apparatus for casting a grey iron or semi-steel hub around the center of a centrally apertured metallic wheel structure such as a disc or an assembly of spokes in such a manner as to form therewith a substantially unitary construction.

Another object of the invention is to provide an improved apparatus for clamping relatively tightly mold sections together with a steel disc between them so that variations in the thickness of the metal are compensated for to prevent leakage of the molten metal between the mold sections. Also clamping means is provided to clamp a corrugated disc between mold sections having corrugated rims to compensate for variations in the corrugations of the disc, as well as the thickness of metal forming the disc, to prevent leakage of molten metal.

A further object of the invention is to provide a method and apparatus which may be worked with either permanent metallic molds or dry sand molds for clamping the metallic wheel structure between the mold sections.

Another object of the invention is to pro-

duce a simple and efficient apparatus for the above purposes which can be quickly operated.

In the following description and annexed drawings the invention is described as applied to the formation of a grey iron or semi-steel hub upon a corrugated sheet metal disc.

In the annexed drawings:

Fig. 1 is a perspective view of the sand mold.

Fig. 2 is an axial section through the mold showing the disc clamped between the mold sections and the hub as cast within the mold.

Fig. 3 is an axial section through the mold cope.

Fig. 4 is a bottom plan view of the cope.

Fig. 5 is an axial section through the mold core.

Fig. 15 is a detail view showing the connection of one of the standards to the base of the press.

Referring to the annexed drawings, the mold employed for casting a hub upon the metallic wheel structure comprises a cope 1, a drag 2 and a core 3. In the drawings is indicated by way of example a sand mold preferably a dry sand mold with a suitable binder, as is well-known, though a metallic or permanent mold may be used if desired.

The cope 1 is composed of sand pressed into the form of a cylindrical block with a flat upper face 4 and a central recess or pouring gate 5, from the bottom of which are narrow passages 6 for the molten metal extending outwardly and then downwardly into the hub forming recess on the under side of the cope. The under face of the cope is provided with a central projection 7 in the form of a truncated cone, the flat lower face of

which when the mold is assembled rests upon the upper surface of the core 3. Surrounding the central projection 7 on the under face of the cope 1 is an annular depression 8 which has a flat bottom to form the inner face of the hub and which is surrounded by a rim 9 shaped to fit the disc or wheel structure upon which the hub is to be cast. In the case shown the rim is corrugated to fit corrugations upon the disc. Air vents 10 extend from the annular depression 8 to the upper face of the cope to permit escape of gases from the interior of the mold during the casting operation.

15 The drag 2 is a cylindrical block of sand of the same diameter as the cope 1, provided with a flat lower face 11 and having its upper side formed with a corrugated rim portion 12 within which is a flat bottomed annular depressed portion 13 for forming the outer hub plate. A series of regularly spaced square bosses or projections 14 are formed upon the flat bottom of the portion 13, which serve to form countersinks in the outer face 20 plate for the heads of attaching bolts. A core centering recess 15 having a flat bottom and a conical wall is formed at the center of the drag 2. The upper portion of the recess 15 is enlarged, forming a shoulder 16 intermediate the top and bottom of the recess 15, and the wall of the enlarged portion is rounded to correspond to the rounded outer face of the hub flange.

25 The core 3 is formed to provide at its lower end a supporting and centering body portion 17 in the form of a truncated cone adapted to fit within the lower portion of the recess 15 in the drag with its flat bottom face resting upon the flat bottom of the recess 15. Projecting outwardly and inclined upwardly from the body portion 17 is a flange portion 18 having its lower face curved to correspond to the curved upper portion of the wall of the recess 15 in the drag. The downwardly projecting portion of the body 17 of the core 3 is of sufficient height to space the flange 18 above the upper portion wall of the recess 15 when the core is placed therein at a distance corresponding to the thickness of the hub flange to be cast in the mold. Projecting radially outward from the edge of the circular flange 18 are a series of regularly spaced long and short projections 19 and 20, which serve to form recesses within the cast hub to lighten the same. A recess 21 is formed in the top of the core within the upwardly inclined flange 18 to receive the central projection 7 on the under side of the cope. The diameter of the flat bottom of the recess 21 is somewhat greater than that of the bottom face of the projection 7, so that the upper face of the flange 18 is spaced from the conical face of the projection 7 at a distance corresponding to the thickness of the inner

flange of the hub to be cast. A series of regularly spaced apertures 22 are formed through the flange 18 for the purpose of forming a series of rivet like integral stiffening members between the inner and outer flanges of the hub.

In assembling the parts for casting the hub upon a corrugated disc for example, the corrugated disc 23 is laid upon the drag 2 with its corrugations fitting in the corrugated rim 12 thereof and with its central aperture 24 centered with respect thereto. The core 3 is then placed upon the drag 2 with its centering projection 17 extending through the aperture 24 of the disc and resting upon the bottom of the recess 15 in the drag, and with its long radial projections 19 positioned within alternate depressions in the corrugated disc 24 and with its short projections 20 within intermediate depressions opposite the countersink, forming projections 14 in the depressed portion of the drag 2. The cope 1 is then placed upon the top of the disc 23 with its central projection 7 resting upon the bottom of the recess 21 of the core and with its corrugated rim portion 9 fitting upon the upper face of the disc. A suitable gas vent is provided in the bottom of the mold by a passage 10^a extending from the interior of the core 3 through the bottom wall of the drag 2.

In casting the molten metal is poured into the gate 5 and runs through the passages 6 to the chamber formed by the complementary recesses in the cope and drag. The circumferentially disposed passages 6 have their outlets into the mold chamber within the central aperture 24 of the disc 23, so that the molten metal is free to flow between the edge of the aperture 24 and the projection 7 to the recesses in the drag 2. Metal from the passages 6 flows into the space between the upper face of the disc 23 and the flat bottom of the depression 8 in the cope 1 and around the radial projections 19 and 20 in the depressions of the disc, to form the inner face plate 25 of the hub; between the central projection 7 of the cope 1 and the flange 18 of the core to form the inner flange 26 of the hub; through the aperture 24 of the disc 23 into the annular flat bottomed outer portion 13 and around the projections 14 therein to form the outer face plate 27 of the hub with the countersinks 28 therein; between the flange 18 and wall of recess 15 in the drag 2 to form the outer flange 29 of the hub; and through the apertures 22 in the flange 18 of the core to form the rivet like stiffening connections 30 between the flanges 26 and 28 of the hub. The projections 19 and 20 serve to provide recesses within the casting in the depression on the inner side of the disc. The short recesses in the casting opposite the countersinks 28 leave the casting solid opposite the counter-

sinks 28, so that the bolt holes can be drilled through solid metal and the bolts will draw upon solid portions of the casting. After the hub is cast the cope 1 and drag 2 are 5 removed and may be used again. The cores 3, however, are broken up in removal from the casting.

When a wheel structure such as a disc is used between the parts of the mold the mold 10 must be forced together with sufficient pressure to compensate for the variations in the thickness of the metallic stock of the disc to prevent leakage of molten metal between the rims of the mold sections and upon the disc. 15 Also in case a corrugated disc or relatively thin metal be used, it is somewhat flexible or yieldable laterally in the hills and valleys of the corrugations near the central aperture of the disc. In the molding operation, 20 therefore, it is necessary that sufficient pressure be applied to compensate for relatively slight irregularities in the corrugations. These may be due either to defects in the dies forming the corrugations or to the grain 25 or physical condition of the metallic stock used, for it is well-known that in forming discs from sheets having a grain structure, even though the dies be perfect certain of the corrugations have a tendency to spring 30 or distort slightly so that when the disc is removed from the dies the corrugations are not all uniform in curvature. Also, the pressure must force the mold sections sufficiently tightly together to clamp the discs 35 between them to compensate for any differences in contour between the corrugations of the mold sections and corrugations of the discs. It will thus be seen that with the use of my molds and press herein disclosed according to my method the mold sections 40 will clamp between them a metallic structure contacting with a relatively large portion of the opposing mold surfaces sufficiently tightly to compensate for irregularities in such structure and prevent leakage 45 of molten metal from the mold.

To secure means for forcing the mold sections together to clamp the wheel structure between them I have provided the mold press shown in Figs. 13, 14 and 15 for holding the molds during the casting of the hub. The mold press has a base 31 upon which is mounted a fluid cylinder 32, preferably pneumatic, provided with suitable connections 50 for admitting and relieving pressure beneath the piston 33 which has a rod 34 extending through the upper end of the cylinder. The piston rod 34 has a rounded upper end 35 upon which is supported the drag engaging 55 plate 36 provided with a rounded socket 37 in the bottom thereof fitting upon the rounded end of the piston rod 34. Standards 38 are attached to collars 39 journaled upon pins 40 at the ends of the base 31. The collars 39 have lateral lugs 41 in which are

mounted set screws 42 engaging lugs 43 upon the ends of the base 31. By adjusting the set screws 42 the inclination of the standards can be varied. A cross bar 44 connects the upper ends of the standards 38 and is 70 adjustably supported at its ends by lower nuts 45 and held upon the nuts 42 by upper nuts 46 and 47. The central portion of the cross bar 44 is enlarged to provide a flat plate 48 to engage the upper face of the 75 cope. After the mold sections are assembled upon the disc 23, the mold is placed upon the supporting plate 36 and pressure applied to the piston 33 to force the mold into engagement with the upper plate 48. By reason of the ball and socket connection between the piston rod 34 and the plate 36 a substantially uniformly distributed pressure is applied to the mold. By so distributing the pressure I am enabled to apply considerable pressure even to sand molds without injury thereto, and by applying pressure to the molds the joints between the contiguous faces of the mold sections and disc are made tight, so that there is no leakage of metal 90 between them.

By way of example I have found that good results may be obtained by applying a pressure of approximately eighty pounds per square inch to the surfaces of sand 95 molds, for such pressure substantially prevents leakage between the mold sections. It is to be understood, however, that the pressure may be varied for the various sizes of molds and material clamped between the 100 mold sections.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

Having described my invention, what I claim is:

1. The process of molding which consists in applying a relatively high pressure to the parts of a sand mold, to clamp an intervening metallic member therebetween and molding metal around such member.

2. The method of casting a metallic hub upon a metallic wheel which consists in forming complementary sand mold sections, having their opposed faces formed to receive between them the part of the wheel surrounding a central aperture, and having complementary recesses to receive the metal to form the hub, clamping the wheel between said mold sections, applying pressure to the mold sections, and pouring molten metal into the molds to form the hub.

3. The method of casting a metallic hub upon a metallic wheel having a central aper-

- ture which consists in forming sand mold sections having their opposed faces formed to receive between them the part of the wheel which surrounds said aperture, and 5 provided with complementary recesses conforming to the outer faces of the hub to be cast, forming a sand core conforming to the interior portion of the hub, assembling said mold sections with the wheel and core between them applying pressure to the mold sections, pouring molten metal into the mold to form the hub, permitting said metal to cool and solidify, and removing said mold sections.
- 15 4. The method of casting a metallic hub upon a corrugated disc having a central aperture which comprises forming a sand mold drag with a peripheral rim portion corrugated to conform to the contour of the 20 disc, and with a depressed portion inside the rim, the outer portion of which conforms to one side of the hub and the center of which forms a core receiving and centering portion, forming a core corresponding to the 25 interior portion of the hub and a cope having a rim portion corresponding to the contour of the disc, and a depressed portion corresponding to the opposite face of the disc, positioning the disc upon the drag, 30 inserting the core through the aperture of the disc into engagement with the centering portion of the drag, placing the cope upon the upper surface of the disc, applying pressure to the cope and drag to firmly clamp them upon the disc, and pouring molten 35 metal into the mold.
5. A sectional mold comprising a drag having its upper face formed to provide a rim portion, a depression at its center, a 40 core member seated in said depression and provided with a flange, a cope having its lower face provided with a rim corresponding to the rim of the drag, said cope having a member to engage the center of the core, and said core having a flange spaced from 45 both the cope and drag to form discs when the metal is poured.
6. A sectional mold comprising a drag and cope, each having complementary corrugated rim portions for engaging with a corrugated metallic disc, one of said mold sections having a depression and the other a projection, a core fitting in the depression of one, and receiving the projection of the other, and having a flange extending between said sections, said sections of the core

being shaped to mold a centrally apertured pair of hub plates around the center of said metallic disc.

7. A sectional mold for hubs comprising a drag having its upper face formed to provide a rim portion, a depressed portion inside the rim and a deeper depression at its center, a core member seated in said depression and provided with a flange overhanging and spaced from said depressed portion, and a cope having its lower face provided with a rim portion corresponding in contour to the rim of the drag, an annular depressed portion inside the rim, and a central core engaging projection, said cope having a pouring gate formed therein.

8. A sand mold for casting a metallic hub upon a corrugated disc, comprising a drag having its upper face formed with a rim portion corrugated to conform to the contour of the disc, a central core receiving and centering recess, and a shallow recess surrounding said centering recess, a core having a projecting portion adapted to fit in said centering recess, a flange adapted to overhang said shallow recess, and radial projections from the flange adapted to extend within corrugations of the disc, and a cope having a central projection engageable with said core, a shallow recess surrounding said projection and a rim portion corrugated to conform to the contour of the disc, said cope being formed with a pouring gate.

9. A sectional mold comprising a cope and drag having rim portions, depressions in said sections, a core member engaging the cope and drag, and having an overhanging flange spaced between said depressions, said core having apertures therethrough connecting with said depressions to form integral connecting members between the spaced discs formed in the depressions by the molten metal.

10. The method of casting a metallic part upon a metallic body which consists in forming complementary sand mold sections having their opposed faces formed to receive between them the metallic body and having complementary recesses to receive the metal to form the metallic part, clamping the metallic body between said mold sections, applying pressure to the mold section, and pouring metal into the molds to form the metallic part.

In testimony whereof I affix my signature.
ALEXANDER P. VREELAND.
